(57) **CLAIM**

We claim the ornamental design for a disposable absorbent article, as shown and described.

DESCRIPTION

FIG. 1 is a plan view of one embodiment of a disposable absorbent article according to our new design, in a laid flat condition and showing the surface of the article that faces away from the wearer.

FIG. 2 is a plan view of another embodiment of the disposable absorbent article according to our new design, in a laid flat condition and showing the surface of the article that faces away from the wearer, wherein phantom lines indicate an area which includes a pattern therein.

FIG. 3 is a plan view of the disposable absorbent article of FIG. 1, showing the surface of the article that faces the wearer when the absorbent article is worn.

FIG. 4 is a side perspective view of the disposable absorbent article of FIG. 1, with the refastenable fastening system shown engaged on both sides of the absorbent article.

FIG. 5 is a front elevation of the disposable absorbent article of FIG. 1.

FIG. 6 is a rear elevation of the disposable absorbent article of FIG. 1.

FIG. 7 is a right side elevation of the disposable absorbent article of FIG. 1.

FIG. 8 is a left side elevation of the disposable absorbent article of FIG. 1.

FIG. 9 is a top plan view of the disposable absorbent article of FIG. 1; and,

FIG. 10 is a bottom plan view of the disposable absorbent article of FIG. 1.
